US0D1080653S

(12) **United States Design Patent** (10) **Patent No.:** **US D1,080,653 S**
(45) **Date of Patent:** **** Jun. 24, 2025**

(54) **DISPLAY PANEL WITH GRAPHICAL USER INTERFACE**

(71) Applicant: **Samsung Display Co., Ltd.**, Yongin-si (KR)

(72) Inventor: **Che Ryong Hwang**, Yongin-si (KR)

(73) Assignee: **Samsung Display Co., Ltd.**, Yongin-si (KR)

(**) Term: **15 Years**

(21) Appl. No.: **29/888,022**

(22) Filed: **Mar. 27, 2023**

(30) **Foreign Application Priority Data**

Feb. 23, 2023 (KR) 30-2023-0006858

(51) **LOC (15) Cl.** **14-04**

(52) **U.S. Cl.**

USPC **D14/485**

(58) **Field of Classification Search**

USPC D14/485-495

(57) **CLAIM**

The ornamental design for a display panel with graphical user interface, as shown and described.

DESCRIPTION

The FIGURE is a front view of the display panel with graphical user interface showing an image according to the present design.

The broken lines depict a display panel and form no part of the claimed design.

1 Claim, 1 Drawing Sheet
